PIN CURL CLIP

Lewis E. Thatcher, Chicago, Ill., assignor to Gaylord Products, Incorporated, Chicago, Ill., a corporation of Delaware

Application October 28, 1950, Serial No. 192,691

7 Claims. (Cl. 132—46)

1

This invention relates to pin curl clips adapted for use in holding spirally wound strands of hair, and has for an object the provision of a clip which is simple and inexpensive to manufacture.

Briefly, the present invention comprises a pair of members blanked and formed from thin sheet metal and pivotally connected intermediate their ends, the forward portions of the members being formed to receive and clamp a pin curl and the rearward portions of the members being formed for engagement by the fingers of the user to pivot the forward portions away from each other. One of the members is formed with offset portions for pivotal engagement in bearing recesses formed in the other member, and the two members are held in assembled relation by means of a resilient rubber band which encircles the forward portions of the members adjacent their point of pivotal engagement.

This invention embodies other novel features, details of construction and arrangement of parts which are hereinafter set forth in the specification and claims, and illustrated in the accompanying drawing, wherein:

Fig. 1 is a perspective view illustrating a pin curl clip embodying features of the present invention.

Fig. 2 is a transverse sectional view taken along the line 2—2 of Fig. 1.

Fig. 3 is a perspective view illustrating a modified form of this invention.

Fig. 4 is a transverse sectional view taken along the line 4—4 of Fig. 3.

Fig. 5 is a perspective view illustrating another modified form of this invention.

Fig. 6 is a transverse sectional view taken along the line 6—6 of Fig. 5.

Fig. 7 is a side elevational view illustrating another modified form of this invention in which the forward portion of the upper member of the clip is formed curvilinear.

Referring now to the drawing for a better understanding of the present invention and more particularly to Figs. 1 and 2 therein, the hair clip is shown as comprising an upper member 6 and a lower member 7 which are preferably blanked and formed from relatively thin, light weight sheet metal, such as aluminum. The upper member 6 is slit longitudinally along the lines 8—8 and then formed to provide a pair of arcuate bearing portions 9—9 and an intermediate portion 11. The lower member 7 is provided with a pair of ears 12—12 which project upwardly in spaced parallel relation for pivotal engagement against the arcuate bearing portions formed on

2

the upper member 6. The intermediate portion 11 provided on the upper member 6 is bowed downwardly and disposed between the ears 12—12.

The forward ends of the members 6 and 7 are of gradually decreasing width to provide hair clamping portions 13 and 14, respectively, adapted to be engaged against opposite sides of a pin curl. A resilient rubber band 16 is mounted around the hair clamping portions 13 and 14 adjacent the bearing portions 9—9 and ears 12—12 to yieldably resist pivotal movement of the members 6 and 7. The rearward ends of the members 6 and 7 are disposed in spaced relation to provide finger engaging portions 17 and 18 adapted to be pressed toward each other to pivot the hair clamping portions 13 and 14 to their open position to receive a pin curl therebetween. The members 6 and 7 are formed with longitudinally extending beads 19 and 21, respectively, to increase their resistance to bending loads.

It will be noted that the hair clip shown and described is relatively simple and inexpensive in construction and may readily be applied to or removed from a pin curl by merely pressing the finger engaging portions 17 and 18 toward each other. It will also be noted that the resilient rubber band acts to hold the members 6 and 7 in assembled pivotal engagement and also serves as a guard to prevent entanglement of hair between the arcuate bearing portions 9—9 and ears 12—12 during use of the clip.

Referring now to Figs. 3 and 4 in the drawings, a modified form of this invention is shown as comprising an upper member 26 and a lower member 27 blanked and formed from thin sheet metal, the upper member being provided with a hair clamping portion 28 and finger engaging portion 29, and the lower member being provided with a hair clamping portion 31 and finger engaging portion 32. The upper member is formed with an arcuate bearing portion 33 and with side flanges 34—34, and the lower member is formed with a pair of upturned ears 36—36 for pivotal engagement against the bearing portion 33. The side flanges 34—34 are disposed along the remote sides of the ears 36—36 to hold the members 26 and 27 in alignment and to prevent displacement of the ears from the arcuate bearing portion 33. A resilient rubber band 37 is engaged around the inner ends of the hair clamping portions 28 and 31 of the members 26 and 27 to yieldably resist opening of the clip and to secure the members in assembled pivotal relation. This form of the invention is otherwise similar to the form heretofore described and illustrated in Figs. 1 and 2 in the drawing.

Figs. 5 and 6 in the drawing illustrate another modified form of this invention in which the clip is shown as comprising an upper member 41 and lower member 42 blanked and formed from sheet metal. The upper member 41 is slit and formed intermediate its ends to provide a pair of arcuate pivot portions 43-43 and an arched bridge portion 44. The lower member 42 is slit and formed intermediate its ends to provide a pair of bearing portions 46-46 and an arched bridge portion 47. The members 41 and 42 are provided with hair clamping portions 48-48a respectively, and with finger engaging portions 49-49a, respectively. A resilient rubber band 51 is mounted around the hair clamping portions 48-48a to hold the upper and lower members in assembled pivotal engagement and to yieldably resist opening of the clip. In this form of the invention the pivot portions 43-43 on the upper member are pivotally engaged against the bearing portions 46-46 on the lower member, and the arched bridge portion 47 is disposed between the pivot portions 43-43 to prevent lateral displacement of the members. This form of the invention is otherwise similar to the two forms heretofore described and illustrated in Figs. 1 to 4 in the drawings.

Fig. 7 in the drawing illustrates another modified form of this invention in which the clip is shown as comprising an upper member 56 pivotally engaged at 57 to a lower member 58, as heretofore shown and described in connection with the preceding forms. The forward end of the upper member 56 is formed with two bow portions 59 and 61 to coact with the forward end of the lower member 58 in clamping a pin curl. The members 56 and 58 are held in assembled pivotal engagement by means of a resilient rubber band 62, as heretofore described.

In the several forms of this invention, it will be noted that the two members forming the clip are adapted to be simply and inexpensively blanked and formed from thin sheet metal and engaged for pivotal movement by a resilient rubber band which also serves to yieldably resist opening movement of the members and to prevent entanglement of hair within the pivot joint.

While this invention has been shown in several forms, it is obvious to those skilled in the art that it is not so limited but is susceptible of various changes and modifications without departing from the spirit and scope of the claimed invention.

I claim as my invention:

1. In a pin curl clip, a pair of members adapted to be blanked and formed from sheet metal, one of said members being formed intermediate its ends with a pair of offset pivot portions, the other of said members being formed intermediate its ends with a pair of transversely spaced arcuate bearing portions to receive said offset pivot portions, and a resilient rubber band mounted around and yieldably resisting pivotal movement of said members, said other member being formed with a boss disposed between said bearing portions to coact with said pivot portions to prevent lateral displacement of said members.

2. In a pin curl clip, a pair of members blanked and formed from sheet metal, said members being pointed at their forward ends and of increasing width toward their rearward ends, one of said members being provided with a pair of pivot posts disposed in spaced transverse alignment, the other of said members being engaged between said pivot posts and formed with arcuate bear-

ing portions to receive said posts, and a resilient rubber band mounted around said members to hold said posts within said bearing portions and to yieldably hold the forward ends of the members in clamping engagement, said pivot posts and bearing portions being disposed intermediate the ends of said members.

3. In a pin curl clip, a pair of members adapted to be blanked and formed from sheet metal, one of said members being formed intermediate its ends with a pair of spaced pivot portions, the other of said members being bowed outwardly along each of its side edges and intermediate its ends to provide a pair of spaced arcuate bearing portions to receive said pivot portions, the portion of said other member between said arcuate bearing portions being engaged against adjacent sides of said pivot portions to prevent lateral displacement of said members, a resilient rubber band mounted around and yieldably resisting pivotal movement of said members, the forward ends of said members being normally disposed in clamping engagement, and the rearward ends of said members being disposed in spaced relation and adapted to be manually pressed together to open the clip.

4. In a pin curl clip, a pair of members adapted to be blanked and formed from sheet metal, one of said members being formed intermediate its ends with a pair of spaced pivot posts, the other of said members being bowed outwardly intermediate its ends to provide an arcuate bearing portion to receive said pivot posts and bowed inwardly along its side edges to engage remote sides of the pivot posts, a resilient rubber band mounted around and yieldably resisting pivotal movement of said members, the forward ends of said members being normally disposed in clamping engagement, and the rearward ends of said members being disposed in spaced relation and adapted to be manually pressed together to open the clip, said rubber band being disposed in front of and adjacent said pivot posts, the forward ends of said members being of progressively decreasing width.

5. In a pin curl clip, a pair of members adapted to be blanked and formed from sheet metal, one of said members being formed intermediate its ends with a pair of offset pivot portions, the other of said members being formed intermediate its ends with a pair of arcuate bearing portions to receive said offset pivot portion, and a resilient rubber band mounted around and yieldably resisting pivotal movement of said members, the latter member being bowed inwardly along each of its side edges to provide spaced bosses engaging the remote sides of said pivot portions to prevent lateral displacement of said members.

6. In a pin curl clip, a pair of members adapted to be blanked and formed from sheet metal, one of said members being bowed inwardly along each of its side edges and intermediate its ends to provide a pair of spaced pivot portions, the other of said members being formed intermediate its ends with a pair of arcuate bearing portions to receive said offset pivot portion, and a resilient rubber band mounted around and yieldably resisting pivotal movement of said members, the latter member being formed with a boss to coact with said pivot portions to prevent lateral displacement of said members.

7. A pin curl clip comprising a pair of members adapted to be blanked and formed from sheet metal, one of said members being formed intermediate its ends with a pair of transversely

spaced pivot portions, the other of said members being slit longitudinally and bowed intermediate its ends to define three arcuate sections one of which is curved reversely from the other sections, each pivot portion being seated within one of said sections and having one surface thereof engaged by one edge of an adjacent section to prevent relative lateral movement of said members, and a resilient band extending around said members adjacent said pivot portions to yield- 10

ably resist pivotal movement of said members.
LEWIS E. THATCHER.
